W. A. JONES

WICK FOR COOKING AND HEATING STOVES

Filed Jan. 13, 1927

FIG. 1.

FIG. 2.

Inventor

W. A. Jones.

By

Alfred J. Randolph Jr.

Attorney

UNITED STATES PATENT OFFICE.

WILLIAM A. JONES, OF MIAMI, FLORIDA.

WICK FOR COOKING AND HEATING STOVES.

Application filed January 13, 1927. Serial No. 160,876.

This invention relates to and has for one of its objects to provide a wick for cooking and heating stoves which shall be non-combustible and capable of efficient use for a long time with little or no attention and which may be manufactured and sold at a comparatively low cost.

With the foregoing and other objects in view the invention consists of the novel construction and arrangement of parts herein-after fully described and claimed, and illustrated in the accompanying drawing, wherein:

Figure 1 is a view in side elevation of a wick constructed in accordance with my invention, and

Figure 2 is a sectional view taken on a plane extending vertically and centrally through the wick.

The wick is cylindrical and comprises a lower portion 1 made of cotton and an upper portion 2 made of asbestos fabric. The lower portion 1 is of greater length than the upper portion 2, and the contiguous edges of said portions are woven together as indicated at 3. A perforated raiser plate 4 is applied to the wick portion 1 and extends from a plane located immediately above the united contiguous edges of the portions 1 and 2 to the lower edge of the portion 1.

As the portion 2 is made of asbestos fabric and has its lower end woven to the upper end of the wick portion 1, there is no necessity for the use of a form maintaining element or elements in connection with said upper portion. The asbestos upper portion 2 thereof renders the wick non-combustible, and as said portion is made of asbestos fabric the wick will last for several years and will require little or no attention. The wick produces a blaze as efficient as those produced by cotton wicks, and when the fuel is exhausted the blaze will be quickly extinguished. The wick can be made in all sizes to fit standard makes of cooking or heating stoves.

What is claimed is:—

A cylindrical wick comprising a lower cotton portion, an upper portion made of asbestos fabric and of less length than the lower portion, the upper portion being woven at its lower edge to the upper edge of the lower portion, and a raiser ring extending from a point slightly above the lower edge of the upper portion to the lower edge of the lower portion.

In testimony whereof I affix my signature.

WILLIAM A. JONES.
